HANDBAG CLOSURE CLASP

Etienne Aigner, 217 Haven Ave., New York, N.Y.

Filed June 27, 1963, Ser. No. 75,556

Term of patent 14 years

(Cl. D87—2)

FIG. 1

FIG. 3

FIG. 1 is a front elevational view of a handbag closure clasp, showing my new design;

FIG. 2 is a side elevational view thereof; and

FIG. 3 is a vertical sectional view taken on the line 3—3 of FIG. 1.

I claim:

The ornamental design for a handbag closure clasp, substantially as shown.
